UNITED STATES PATENT OFFICE.

OLIVER C. HENRY, OF POCATELLO, IDAHO.

CABINET BED.

Application filed April 12, 1924. Serial No. 706,063.

To all whom it may concern:

Be it known that I, OLIVER C. HENRY, a citizen of the United States, residing at Pocatello, in the county of Bannock and

5 State of Idaho, have invented certain new and useful Improvements in Cabinet Beds, of which the following is a specification, reference being had to the accompanying drawings.

10 This invention relates to certain improvements in cabinet beds and it is an object of the invention to provide a novel and improved device of this general character especially designed and adapted for use in 15 apartments or other locations wherein it is of particular advantage to save space.

It is also an object of the invention to provide a novel and improved device of this general character comprising a cabinet and 20 a bed structure, wherein the bed structure is so constructed as to be readily compacted and housed within the cabinet when not in use, said cabinet being also constructed to permit the top thereof to be employed in the 25 fashion of a dresser or kindred article of bedroom furniture.

The invention consists in the details of construction and in the combination and arrangement of the several parts of my improved cabinet bed whereby certain important advantages are attained and the device rendered simpler, less expensive and otherwise more convenient and advantageous for use, as will be hereinafter more fully set 35 forth.

The novel features of my invention will hereinafter be definitely claimed.

In order that my invention may be the better understood, I will now proceed to 40 describe the same with reference to the accompanying drawings, wherein:—

Figure 1 is a view in perspective of a cabinet bed constructed in accordance with an embodiment of my invention, the bed structure proper being extended for use; 45

Figure 2 is an enlarged fragmentary view in top plan showing the means herein disclosed for holding the hingedly connected sections of a side member in extended relation;

Figure 3 is an enlarged view partly in section and partly in elevation illustrating the bed structure compacted and housed within the cabinet;

50 Figure 4 is a fragmentary view partly in section and partly in top plan illustrating

in detail the means as herein disclosed for engaging with the head end portion of the bed structure the rear or back wall of the cabinet;

Figure 5 is a fragmentary view in perspective of the center member comprised in each of the hinge sections of a side rail of the bed structure and the brace or tie member associated therewith.

As disclosed in the accompanying drawings, C denotes a cabinet of requisite dimensions and having its top wall 1 flat so that the same can be used after the fashion of a dresser or other bedroom furniture, although not illustrated in the accompanying drawings a mirror may be mounted upon the cabinet to facilitate its use for toilet purposes.

The bottom and front face of the cabinet C are open and said open face is adapted to be closed in a conventional manner by the swinging doors 2. The cabinet C as herein disclosed is also provided with the casters 3 whereby the device may be readily shifted from one location to another as may be preferred although I do not wish to be understood as limiting myself in this respect because any desired cabinet may be permanently built within a room.

The inner face of the rear or back wall 4 of the cabinet C closely adjacent to the sides thereof is provided with the vertically disposed cleats or beams 5, the upper portion of each of which being provided in its outer face with the longitudinally disposed groove 6 substantially circular in cross section and provided with a restricted entrance slot 7. The lower end of the slot 7 terminates at a distance above the lower end of the cleat or beam 5 at the point of elevation it is desired to have the head of the bed structure supported when such structure is extended for use.

Freely moving within each of the grooves 6 is a head 8 herein disclosed as substantially spherical in form and which carries an arm 9 extending a desired distance inwardly of the cabinet C through the entrance slot 7. The outer end portion of the arm 9 extends within the kerf 10 formed in an end portion of a rod 11, said rod 11 and arm 9 being pivotally connected, as at 12, for relative swinging movement by a rivet or kindred member. The rod 11, as herein disclosed, is telescopically engaged within the adjacent end portion of a side rail sec-

tion 14 and threaded through a wall of the rail section 14 and engaging the inserted portion of the rod 11 is a holding screw 15 whereby the rod 11 may be effectively locked 5 at a desired longitudinal adjustment with respect to the rail section 14. The adjacent end portions of the rail sections 14 are connected by the head cross member 16. Each of the side rails S of the bed structure comprises the two sections 14 and 17, the section 17 being of a length less than that of the section 14. The inner or adjacent ends of the sections 14 and 17 are pivotally connected, as at 18, with the opposite end portions of the elongated center pieces 19 herein disclosed as in the form of an inverted T in cross section.

In the present embodiment of my invention, the web flange 20 of the center piece 20 19 has each of its end portions received within a kerf produced in the associated end portion of a rail section 14 or 17.

The center piece 19 is of a length substantially equal to twice the thickness of each 25 of the mattress sections M so that when the bed structure is folded or compacted, as is illustrated in Figure 3, the overlying mattress sections M will fit substantially snug between the folded sections 14 and 17.

30 The center pieces comprised in both of the side rails S are tied or connected by the brace or stay rod 21. The portion of said rod between the pieces 19 being offset as indicated in Figures 1 and 5 in order to offer no hindrance or obstruction to the bed spring fabric 22 when weight is imposed thereon. The outer ends of the sections 17 of the side rails are connected by the foot rail 23 and carried by said outer 35 end portions of the sections 17 is the foot piece 24 herein disclosed as substantially in the form of an inverted U and having each of its side members consisting of two hingedly connected sections 25 and 26, the 40 adjacent ends of said sections being connected by a retractile member 27, herein disclosed as a coil spring. The section 26 is secured directly to a section 17 and is of a length substantially equal to the thickness 45 of the mattress section M so that when the bed structure is to be compacted the upper portion of the head piece may be swung to overlie the adjacent end portion of a mattress section to hold the same against 50 displacement particularly during the period when the bed structure is being compacted, said upper portion of the head piece being maintained in clamping action upon the mattress section by each of the springs 27.

55 Hingedly connected, as at 28, with the outer end portion of each of the sections 17 of the side rails S is a supporting leg 29 and both of these legs 29 are connected for unitary swinging movement by the brace member 30. Each of the legs 29 and the

adjacent section 17 has operatively engaged therewith an articulated brace member 31.

The inner end portions of the sections 14 also have pivotally connected therewith as at 32, the supporting legs 33 connected for unitary swinging movement by the brace member 34. Each of these legs 33 and the adjacent section 14 have associated therewith an articulated member 35.

When the sections 14 and 17 of each of the side rails S are extended the outer section 17 is held against sagging movement relative to the adjacent center piece 19 by the rigid strap 36 pivotally connected, as at 37, with the underside of the inner end portion of the section 17 and which is adapted to be swung into a position to underlie the center piece 19. The side marginal portion of the strap 36 adjacent its free end being provided with an open recess 38 to receive a headed shank 39 depending from the center piece 19 whereby the strap 36 is effectively maintained in working position.

Secured to the opposite end portions of the head rail 16 are the flexible members 40 both operatively connected with the flexible member 41. The member 41 extends upwardly and over a pulley 42 depending from the top 1 of the cabinet C.

With the bed extended, as illustrated in Figure 1 and it is desired to compact and house the same within the cabinet C, and after the legs 29 and 33 have been folded into inoperative position and each of the irons 36 swung into release position, pull is imposed upon the flexible member 41 causing the arms 9 and the adjacent end portions of the sections 14 of the side rails S to move upwardly to a point closely adjacent to the top 1 of the cabinet C whereupon the foot portion of the bed is swung to a position overlying the head portion of the bed with the mattress sections M arranged therebetween as illustrated in Figure 3. Before the foot portion of the bed structure is swung into folded position the upper portion of the foot piece 24 is caused to overlie the outer end portion of the adjacent mattress section as is also illustrated in Figure 3. After the compacted bed has been housed within the cabinet C the doors 2 may be readily closed.

With the bed structure housed within the cabinet C the easter 43 carried by the central portion of the brace or stay member 21 has direct contact with the floor or other surface upon which the cabinet C is positioned whereby the weight of the bed structure proper is carried directly upon said floor or kindred supporting surface.

In order to maintain the foot portion of the bed in its folded position with respect to the head portion thereof I secure to the central portion of the foot rail 23 a flexible

member 44 the opposite or free end of which being provided with the hook member 45 adapted to be engaged with the head rail 16.

5 By having the rods 11 telescopically engaged with the side sections 14, the bed structure proper when desired may be moved outwardly a distance to position said structure entirely exterior of the cabinet C when

10 the bed is extended and assembled for use.

15 The bed bottom spring fabric 22 may be of any ordinary or preferred construction and is attached to the head rail 16 and the foot rail 23 in any manner preferred.

20 From the foregoing description it is thought to be obvious that a bed cabinet construction in accordance with my invention is particularly well adapted for use by reason of the convenience and facility with which it may be assembled and operated, and it will also be obvious that my invention is susceptible of some change and modification without departing from the

25 principles and spirit thereof and for this reason I do not wish to be understood as limiting myself to the precise arrangement and formation of the several parts herein shown in carrying out my invention in

30 practice except as hereinafter claimed.

I claim:—

1. A device of the class described comprising a cabinet having a face open, vertically disposed guideways carried by the opposite face of the cabinet, arms slidably engaged within said guideways, rods pivotally engaged with said arms, a foldable bed structure comprising side rails with which the rods are telescopically engaged, said bed structure when compacted being 35 housed within the cabinet, and means for holding the rods and side rails against relative movement.

2. A device of the class described comprising a cabinet having a face open, vertically disposed guideways carried by the opposite face of the cabinet, arms slidably engaged within said guideways, rods pivotally engaged with said arms, a foldable bed structure comprising side rails with which 50 the rods are telescopically engaged, said bed structure when compacted being housed within the cabinet, and means for holding the rods and side rails against relative movement, the lower ends of the guideways providing supports of the head of the bed when the bed structure is extended for use.

In testimony whereof I hereunto affix my signature.

OLIVER C. HENRY.
